UNITED STATES PATENT OFFICE.

JONATHAN BURGESS, OF MARION, OHIO.

LOOSE-LEAF BINDER.

1,079,039.

Specification of Letters Patent.

Patented Nov. 18, 1913.

Application filed June 10, 1912. Serial No. 762,808.

To all whom it may concern:

Be it known that I, JONATHAN BURGESS, a citizen of the United States, residing at Marion, in the county of Marion and State of Ohio, have invented certain new and useful Improvements in Loose-Leaf Binders, of which the following is a specification.

This invention has relation to loose leaf binders, and has as its object to provide a binder which will hold the leaves as if permanently bound and which may at the same time be readily manipulated so as to permit of removal of any one or all of the leaves; interchange of leaves, or the insertion of new leaves.

A further object of the invention is to provide a binder which will firmly and securely hold a greater or less number of leaves and which will automatically adapt itself to the bulk of the leaves as they are removed.

Further the invention aims to provide novel means for holding the spring-pressed gripping leaf of the binder away from the leaves so that it will not interfere with the removal or insertion of leaves.

In the accompanying drawing:—Figure 1 is a perspective view of the binder embodying the present invention, the gripping leaf thereof being shown raised out of engagement with the leaves to be held; Fig. 2 is a plan view of the binder with the gripping leaf in engagement with the loose leaves; Fig. 3 is a view in side elevation and partly in section of the back portion of the binder; Fig. 4 is a view partly in side elevation and partly in longitudinal section of the binder closed.

Corresponding and like parts are referred to in the following description and indicated in all the views of the accompanying drawing by the same reference characters.

In the drawing the binder is illustrated as including covers one of which is indicated by the numeral 1 and the other by the numeral 2, these covers being connected by a suitable back 3 which may be flexible or stiff, as desired. The leaves to be held are indicated by the numeral 4 and each is formed with two or more spaced openings 5 located near the upper edge of the leaf.

The binder proper consists essentially of a fixed member with which the leaves are assembled and a spring-pressed gripping member which is arranged to bear firmly against the stack of leaves and hold the same

in place. The first mentioned member is formed from sheet metal and includes an attaching portion 6 which at its rear edge is formed with an upstanding flange 7. Rivets 8 are secured through the attaching member 6 and through the cover 1 of the binder and the flange 7 is so positioned as to be covered and concealed by the back 3 when the binder is closed. The flange 7 is formed at intervals at its upper end with pintle lugs 9 and the gripping leaf of the binder which constitutes the second mentioned member thereof is in the form of a plate 10 provided at its lower edge with pintle lugs 11 which engage between pintle lugs 9, a hinge pin 12 being inserted through the said pintle lugs 9 and 11. One or more springs 13 are arranged upon the hinge pin 12 and coiled thereabout and one end of each spring is engaged with the flange 7 as indicated at 14 and its other end bears against the outer side of the plate 10 as indicated at 15. These springs tend to forcibly hold the gripping leaf 10 in engagement with the uppermost leaf of the stack 4.

In order that the leaves may be securely held in place, posts 16 are secured at their lower ends to the attaching portion 6 of the first described member of the binder and project upwardly and through the openings 5 in the stack of leaves 4 and the gripping leaf 10 is formed with openings 17 in which the upper ends of the posts are arranged to engage when the leaf is in gripping engagement with the loose leaves 4, as clearly shown in Fig. 4 of the drawing.

As before stated, means is provided for holding the gripping leaf out of engagement with the loose leaves and in such position that it will not interfere with the removal or insertion of the leaves 4 and this means consists of an arm 18 which is pivoted as at 19 to the rear side of the flange 7 and has at its free end a finger piece 20 which may be grasped for the purpose of swinging the finger upon its pivot. This arm 18 is provided adjacent to its said free end and beside the finger piece 20 with a hooked finger 21 which may be brought into engagement over the upper or free edge of the gripping leaf 10 by first swinging this leaf upon its hinge and then moving the arm 18 upon its pivot 19.

From the foregoing it will be readily understood that when it is desired to remove or insert leaves, the gripping leaf 10 is swung

up against the tension of the springs 13 and the arm 18 is then swung to position with its finger 21 engaged with the free edge of the said leaf 10. The leaf will at such time be supported in substantially the same plane as the flange 7 and will when in such position in no way interfere with manipulation of the leaves 4. In order to close the binder it is only necessary to swing the arm 18 to the right in Fig. 1 of the drawing, whereupon its finger 21 will be brought out of engagement with the leaf 10 and the latter will be automatically swung down by the springs 13 so as to bear against the uppermost leaf 4. After this has been done the arm 18 may be swung to the left in said Fig. 1 so as to lie behind the flange 7, in which position it will not interfere with the closing of the cover 2.

Having thus described the invention what is claimed as new is:

1. In a binder of the class described, a fixed member, a gripping member hinged thereto, a spring yieldably holding said gripping member in engagement with leaves disposed between the members, and an arm pivoted upon the fixed member and having a hooked finger arranged for engagement with the gripping member, whereby to hold the latter out of such engagement with the said leaves, the arm being adapted to be swung upon its pivot to lie beside the fixed member or to extend beyond the said member and in position to engage with the gripping member.
2. In a binder of the class described, a fixed member, a gripping member hinged thereto, a spring yieldably holding said gripping member in engagement with leaves disposed between the members, an arm pivoted to the fixed member and having a finger piece at its free end, and a hooked finger located at the said free end of the arm and arranged for engagement with the gripping member, whereby to hold the latter out of such engagement with the said leaves, the

arm being adapted to be swung upon its pivot to lie beside the fixed member or to extend beyond the said member and in position to engage with the gripping member.

3. In a binder of the class described, a fixed member having angularly positioned wings, one of said wings constituting an attaching means, a gripping leaf hinged to the other wing of the said fixed member, a spring yieldably holding the gripping leaf in gripping engagement with leaves disposed between the same and the attaching wing of the fixed member, and means carried by the second mentioned wing of the fixed member and engageable with the gripping leaf, whereby to hold the same out of gripping engagement with said leaves.

4. In a binder of the class described, a fixed member, a gripping member hinged thereto, means yieldably holding the gripping member in engagement with the leaves disposed between the members, an arm pivoted to the back of the fixed member and arranged to swing transversely thereof whereby to extend above the said member when in swung up position, the said arm being provided with a finger-piece located at its free end and with a hooked finger located at the base of the finger-piece, the said hooked finger being arranged to engage over the free edge of the hinged gripping member when the said gripping member is swung up out of engagement with the leaves and the arm is swung to extend upwardly at an angle, the hooked finger having its terminal so located that when the arm is swung to vertical position, it will disengage from the said hinged gripping member.

In testimony whereof I affix my signature in presence of two witnesses.

JONATHAN BURGESS. [L. s.]
